UNITED STATES PATENT OFFICE.

EMMA D. BAKER, OF NASHVILLE, TENNESSEE.

HAIR CURLER.

1,416,596.

Specification of Letters Patent. Patented May 16, 1922.

Application filed November 18, 1921. Serial No. 516,117.

To all whom it may concern:

Be it known that I, EMMA D. BAKER, a citizen of the United States, residing at Nashville, in the county of Davidson and State of Tennessee, have invented new and useful Improvements in Hair Curlers, of which the following is a specification.

This invention relates to hair curlers, and the primary object of the same is to provide a device of this kind with a main member having a covering of such character as to effectively grip the ends of stubby bobbed hair and hold the latter firmly when the remaining parts of the curler are pressed and secured against the hair thus retained. A further object of the invention is to provide a device of the class set forth in the form of a clasp that can be held in the palm of the hand while rolling the hair, with material advantages in expeditiously applying the hair to the curler in a proper manner.

With these and other objects and advantages in view, the invention consists in the construction and arrangement of parts which will be more fully hereinafter described and claimed.

In the drawing:

Fig. 1 is a perspective view of a hair curler shown open and embodying the features of the invention;

Fig. 2 is a top plan view of the improved hair curler shown closed;

Fig. 3 is a side elevation of the improved curler;

Figs. 4 and 5 are detail views of the two essential parts of the improved hair curler;

Figs. 6 and 7 are plan views of the blanks from which the parts of the hair curler are formed.

The numeral 5 designates the intermediate or middle member having a covering 6 of suitable soft material adapted to operate to effectively hold the ends of the hair applied thereto and the hair as wound thereon. This intermediate or middle member 5 is flat and straight and is continued at one end into a curved bend 7 forming a hollow terminal 8 that provides a spring action for a closing tongue 9 also continuous therewith and projecting along one side of the intermediate or middle member 5 when the curler is properly shaped from the blanks shown by Figs. 6 and 7. The curved continuation or bend 7 between the intermediate or middle member 5 and the closing tongue 9 is formed with a vertical slot 10 opening outwardly through

the upper edge thereof and extending a distance inwardly thereover sufficient to effect a securement of the free end of a clamping member 11, which is positioned on the side 60 of the intermediate or middle member 5 opposite that along which the tongue 9 extends. The intermediate or middle member 5 also continues into a curved bent wall 12 having upper and lower vertical slots 13 and 14 65 and a web 15 between the said slots, the curved wall 12 being continued and formed into a straight terminal 16, which is partially secured to the intermediate or middle member 5 and has a central notch 17 in its 70 free end for movement therethrough of the pointed extremity 18 of the closing tongue 9. The straight terminal 16 projects over the intermediate or middle member 5 a sufficient distance to form an effective keeper 75 for the free end of the closing tongue 9, the free end of the said extremity 16 being loose for insertion between the same and adjacent part of the said intermediate or middle member 5 of the free extremity 18 of the said 80 tongue.

The hollow terminal 8 and the hollow curved wall 12 at opposite extremities of the intermediate or middle member 5, respectively serve as a keeper and for giving the 85 tongue 9 a resilient action, and has a means for hinging the clamping member 11 and enclosing the parts of the hinge. The curved wall 12 is so shaped, or stands out beyond one side of the intermediate or middle member 5 such a distance as to properly space the member 11 from the member 5 for holding the hair between the said members in a positive and reliable manner after the hair has been wound upon or disposed about the said 90 intermediate or middle member and the tongue 9, and as a specific preferred arrangement, the intermediate web 15 between the slots 13 and 14 is formed into an eye, and the adjacent end of the clamping member 11 is 95 slightly bent inwardly, as at 19, and is formed with upper and lower eyes 20 and 21 separated by an intermediate slot 22, the eyes 20 and 21 being disposed in alignment with opposite terminals of the intermediate 100 eye formed from the web 15, and through all the eyes a pivot rod or pintle 23 is inserted and suitably secured. The eyes 20 and 21 and that formed from the web 15 are all located within the area of the curved wall 110 12, or the hollow hinge extremity provided by the said latter wall, so that there is no ex-

terior projection to catch upon the hair and which might interfere with the expeditious manipulation of the hair curler during the application and removal thereof. The free 5 extremity of the clamping member 11 has a vertical slot 24 opening through the lower edge thereof and adapted to engage the slot 10 in the hollow keeper bend or extremity 8, so as to lock the said clamping member 10 closed, the operation being very simple and consisting in pulling upwardly on the member 11 a sufficient distance to register the slot 24 with the slot 10 and then releasing the clamping member 11, which locks itself 15 in resuming its normal position. In releasing the member 11 the same operation is pursued, that is, the said member is pulled upwardly to release it from the hollow keeper bend 8.

20 The improved hair curler is made from two blank parts shown by Figs. 6 and 7, and these parts may be quickly bent or assembled in shape to give the parts of the device the form and operative association hereinbefore described and as clearly shown by Fig. 1. In the operation of the improved hair curler, the closing tongue 9 and clamping member 11 are released and stand outwardly from the intermediate or middle 25 member 5. The ends of the hair are disposed or inserted between the intermediate member 5 and the tongue 9 and the latter is then closed and locked, to tightly clamp the hair ends and especially short ends. After 30 the ends of the hair have thus been secured, the curler is rolled in the palm of the hand until the quantity of hair desired to be curled is applied around the intermediate member 5 and the tongue 9, and after the 35 curler has been properly filled, the clamping member 11 will be closed and tightly secured against the hair thus wound about the intermediate member 5 and the tongue 9. After a certain period, the member 11 will 40 be released from the hair and the curler will be unwound and the hair liberated therefrom by finally releasing the tongue 9, and it will be found that the hair so treated will be given a curled or wave-like form in accordance with the desires of the user.

45 It is proposed to make the improved hair curler of any suitable material having a necessary amount of resiliency. The several parts of the curler may be easily operated, and in the drawings the device is shown on a somewhat enlarged scale to clearly illustrate the several structural features. It will be understood, however, that the curler will be of less dimensions than shown in practice. It is also obvious that the several parts of the curler may be varied.

50 What is claimed as new is:

1. In a hair curler, a main intermediate member having a suitable covering, and a

65 closing tongue and clamping member respectively disposed on opposite sides of the intermediate member and respectively continued from one extremity of the latter and hinged to the opposite extremity through the medium of terminal bends in the form 70 of loops and hinged connecting devices.

2. A hair curler comprising an intermediate straight member having a suitable covering with a looped bend continuing from one extremity thereof and terminating in a 75 closing tongue, the opposite extremity of the intermediate member having a looped bend and a terminal keeper returned partially thereover for engagement by the end of the tongue, and a clamping member 80 hinged to one of the terminal looped bends and having separable clasping engagement with the other bend.

3. In a hair curler, an intermediate straight member having a suitable covering 85 and forming the main support for the hair, said intermediate member being provided at opposite extremities with looped bends, one of the bends continuing into a tongue at 90 one side of the intermediate member and the other bend having an extremity returned partially over the intermediate member to form a securing means for the tongue, and a clamping member hinged at one end to the looped bend which is in part returned 95 over the intermediate member and adapted to be closed parallel with the latter member, the free extremity of the clamping member and the looped extremity opposite that to which the clamping member is hinged being formed with interacting slots to serve 100 as separable catch means for the clamping member.

4. A hair curler comprising an intermediate straight member having a suitable covering, the intermediate member having on one side a tongue formed continuous therewith through the medium of an end loop, the opposite extremity of the intermediate member also having a loop which is formed in 105 part as a catch for the said tongue, and a clamping member having one end and a portion of the end looped member having the catch for the tongue provided with a hinge 110 knuckle held intact by a pintle, the free extremity of the clamping member and the opposite loop having an interacting catch structure for separably retaining the clamping member closed in relation to the intermediate member.

115 In testimony whereof I have hereunto set my hand in presence of two subscribing witnesses.

EMMA D. BAKER.
